UNITED STATES PATENT OFFICE.

JOHN Y. KING, OF LANSDOWNE, PENNSYLVANIA.

AIR-FEEDING DEVICE FOR COAL STOVES.

Application filed September 10, 1920. Serial No. 409,322.

To all whom it may concern:

Be it known that I, JOHN Y. KING, a citizen of the United States, residing at Lansdowne, in the county of Delaware and 5 State of Pennsylvania, have invented new and useful Improvements in Air-Feeding Devices for Coal Stoves, of which the following is a specification.

My invention relates to a new and useful improvement in air feeding devices for coal stoves, and has for its object to provide an exceedingly simple and effective device of this description which may be readily applied to the round eyes of plates of a 15 stove as well as the cross plates and with equal facility may be applied to any other portion of a stove so as to inject air at a high temperature adjacent the fuel bed for intensifying the combustion of said fuel.

20 A further object of my invention is to provide a simple and effective means of attaching the device whereby air will have free passage thereto.

With these ends in view, this invention 25 consists in the details of construction and combination of elements hereinafter set forth and then specifically designated by the claims.

In order that those skilled in the art to 30 which this invention appertains, may understand how to make and use the same, I will describe its construction in detail, referring by numerals to the accompanying drawing forming a part of this application.

35 in which:—

Fig. 1, is a plan view of a portion of the top of a cook stove showing the application of my improvement to several parts thereof.

Fig. 2, is a section at the line 2—2 of 40 Fig. 1.

Fig. 3, is an enlarged plan view of my improved device.

Fig. 4, is a side elevation of Fig. 3.

Fig. 5, is a plan view of the device showing the attaching screw therein.

Fig. 6, is a central section of the device shown as attached to some portion of the stove.

In carrying out my invention as here embodied, 1 represents a hollow drum having two sections of its periphery formed at angles to each other, the outer surface thereof being divided into facets 2 for the purpose hereinafter set forth. With this drum 55 is preferably formed a hub 3 having a threaded hole 4 therethrough leading to the

interior of the drum adapted to receive the threaded portion of the attaching screw 5 which latter has a small passageway 6 formed therethrough, said passageway terminating in the slot 7 in the screw head. By this arrangement the drum may be readily attached to any portion of a stove plate by simply forming a hole through the part to which the device is to be attached 65 and passing the attaching screw 5 through said hole and threading it into the hole 4 in the hub. This construction makes it possible and practicable to attach the device to a stove plate regardless of projections or 70 ribs which may be formed upon the underside of said plate.

8 represents a series of small holes drilled at right angles to the surfaces of the facets on the lower portion of the drum and there 75 may be as many of these holes as desired either one for each facet or a lesser number.

By forming the exterior of the drum as before described the drilling of the holes 8 is greatly facilitated since the facets upon 80 the upper portion of the drum serve as bases upon which to support the drum while the holes of the diametrically opposite facets are being drilled, which will give the proper angle to the holes as will be readily understood.

One of these devices being attached to some suitable part of a stove the air will flow in through the slot 7 and hole 6 to the interior of the drum and be there heated 90 and expanded and projected from the holes 8 in fine jets at a slight downward angle and so intermingle with the gases arising from the coal bed as to greatly increase the intensity of the combustion of said gases 95 and thereby greatly economize in the use of the fuel for a given amount of heat produced. The construction of the drums as here described facilitates the heating of the air passing into said drums and also greatly 100 increases the efficiency of the air projected therefrom since said air being projected in jets from a common center produces a cyclonic action in the gases arising from the coal bed, and in practice several of these 105 drums are utilized in each fire box providing common centers of agitation and the process of properly intermingling the heated air and products of combustion is greatly facilitated.

110 Of course I do not wish to be limited to the exact details of construction as herein

shown as these may be varied within the limits of the appended claims without departing from the spirit of my invention.

Having thus fully described my invention, 5 what I claim as new and useful is:—

1. As a new article of manufacture, an air feeding device consisting of a drum the periphery of which is divided into two sections, each of said sections being sub-divided 10 into facets, the lower facets having holes therethrough at right angles to the faces thereof, and a hub formed with the barrel.

2. In a device of the character described, a drum the periphery of which is divided 15 into two sections, each of said sections being sub-divided into facets, the lower facets having holes formed therethrough at right

angles to their surfaces, an internally threaded hub formed with the drum, and means for attaching said drum to a stove 20 in such manner that it will lie adjacent to the fire bed.

3. In a device of the character described, a drum the periphery of which is divided into two sections, each of said sections being 25 sub-divided into facets, the lower facets having holes formed therethrough at right angles to their surfaces, an internally threaded hub formed with the drum, and a screw adapted to thread into the hub, said 30 screw having a hole therethrough.

In testimony whereof, I have hereunto affixed my signature.

JOHN Y. KING.
